Attest.

UNITED STATES PATENT OFFICE

YALE W. EHRET, OF ELKHART, INDIANA, ASSIGNOR TO THE ADLAKE COMPANY, OF CHICAGO, ILLINOIS, A CORPORATION OF ILLINOIS

SASH LOCK

Application filed February 11, 1931. Serial No. 514,992

When a lock of the so-called starter type is applied to a sash, the starting element of the lock will sometimes cause trouble by not allowing the sealing strip on the bottom rail of the sash to seat snugly against the sill. This difficulty will occur whenever the latching element—which is connected with the starting element—is prevented for any reason from assuming its fully projected position just as the sash approaches the sill.

One of the objects of the present invention is to provide an improved starter type lock which will not interfere in any way with the closing movement of the sash to which applied.

Another object of the invention is to provide certain hereinafter described improvements in lock construction, which improvements, while applicable to locks of the starter type, may also be incorporated in locks of other types.

Still other objects and advantages of the invention will be apparent upon a full understanding of the construction, arrangement and operation of the novel sash lock structure.

One form of the invention is presented herein by way of exemplification, but it will of course be appreciated that the invention is capable of embodiment in other structurally modified forms coming equally within the scope of the appended claims.

In the accompanying drawings:

Fig. 1 is a fragmentary inside face view 35 of a sash equipped with the improved lock, showing the sash in its fully closed position;

Fig. 2 is a similar view, showing the sash in a raised position;

Fig. 3 is a horizontal section through the 40 bottom rail of the sash, taken on the line 3—3 of Fig. 2; and

Fig. 4 is a vertical section through the bottom rail, taken on the line 4—4 of Fig. 1.

The particular starter type lock which is illustrated in the drawings is substantially the same in general features of construction, arrangement and operation as the lock which forms the subject matter of an application for patent filed by Carl H. Larson on January 17, 1931 under Serial No. 509,294, and

will therefore be described but briefly here.

As will be observed, the lock includes a casing plate 10 which is attached to the bottom rail 11 of a sash; an operating lever 12 which is pivoted to the plate at 13 and has a normally inclined handle 14 in vertically spaced relation to a lifting flange 15 on the plate; a normally horizontal projection 16 on the lever which carries an anti-friction roller 17 for engagement with the raised inner portion 18 of the sill of the window frame; and a bolt 19 which is slidably mounted in a horizontal guideway 20 in one end of the bottom rail 11 in a normally projecting position.

The operating lever 12 is connected to the bolt 19 by a link 21. One end of the link 21 is provided with a hole 22 through which a pin 23 on the lever extends, while the other end of the link is provided with an axially elongated slot 24 through which a pin 25 on the bolt extends. The link 21 passes through an apertured end flange 26 on a reinforcing member 27 in the bottom rail, and is encompassed beyond the flange by two coil springs 28 and 29. The spring 28 is compressed between a washer 30 which abuts against the flange 26 and a washer 31 which abuts against a cross pin 32 on the link, and the spring 29 is compressed—but to a less degree—between the inner end of the bolt 19 and a washer 33 which abuts against the pin 32.

When the handle 14 is forced toward the flange 15, the nose of the bolt 19 will be retracted and the roller 17 will be moved downwardly into a position beneath the pivotal axis 13 of the lever, thereby forcing the sash up away from the sill. By reason of the overrunning pin and slot connection between the bolt 19 and the link 21, and the double spring arrangement for holding the bolt normally projected, inward movement of the bolt from any cause other than operation of the lever 12 will be taken up by the yield of the spring 29 only, with the result that the handle 14 will remain in the position shown and the roller 17 will remain in its upwardly retracted position clear of the sill.

While only one side of the sash is shown, it will of course be understood that another lock similar to the one described will or-

dinarily be attached to the other side of the sash and used in conjunction with the lock shown. The side edges of the sash fit within vertically extending guides 34 of any suitable construction, and the outer ends of the bolts 19 of the locks are adapted to project into oppositely disposed recesses 35 in the guides, as shown in Fig. 2, when the sash is to be maintained in a raised position.

When the sash is in its lowermost position, a sealing strip 36 of any suitable construction is adapted to seat snugly against the outer sloping portion 37 of the rail, as shown in Figs. 1 and 4. In this position of the sash it may happen that the latching bolts 19 may be forced inwardly by engagement of the same with the guides 34, either because no recesses are provided in the lower ends of the guides to accommodate the ends of the bolts, or because such recesses are improperly located, or else because the clearance between the sides of the sash and the guides is too small to permit of full projection of the bolts even in the presence of recesses. It will readily be understood that, if the rollers 17 were forced to move downwardly whenever the noses of the bolts 19 were forced inwardly, a weather-tight seal could not be obtained between the bottom rail of the sash and the sill.

With the improved construction herein described, however, this trouble is wholly eliminated. Numerous other advantages derivable from this improved construction, aside from the starting feature combination, will be obvious to those skilled in the art.

I claim:

1. In a sash lock of the starter type, in combination, a starting element, a latching element, and a single finger piece operable to simultaneously project the starting element and retract the latching element, said latching element being retractable upon the application of inwardly directed pressure to the projecting end thereof without causing projection of the starting element.
2. In a sash lock of the starter type, in combination, a latching element, a starting element which is connected with the latching element and is projected when the latching element is retracted, means for retracting the latching element, and a spring in the connection between the latching element and the starting element which yields without projecting the starting element when inwardly directed pressure is applied to the projecting end of the latching element.
3. In a sash lock, a supporting frame, a latching bolt, an operating lever, a link extending between the bolt and the lever, an end-play connection between the link and the bolt, a coil spring acting on the link to move the same in the direction of projection of the bolt, and another coil spring acting on the bolt to take up the slack afforded by the end-play connection in the direction of pro-

jection of the bolt, said coil springs encompassing the link with the first mentioned spring confined between an abutment on the frame and an abutment on the link and with the second mentioned spring confined between an abutment on the link and an abutment on the bolt.

In testimony whereof I have hereunto subscribed my name.
